MOUNTING FOR ADJUSTABLE WORKING MEMBERS.

No. 902,328.

Specification of Letters Patent.

Patented Oct. 27, 1908.

Application filed July 10, 1902, Serial No. 115,010. Renewed September 16, 1908. Serial No. 453,287.

To all whom it may concern:

Be it known that I, FRANCIS H. RICHARDS, a citizen of the United States, residing at Hartford, in the county of Hartford and 5 State of Connecticut, have invented certain new and useful Improvements in Mountings for Adjustable Working Members, of which the following is a specification.

The present invention relates to mountings for members which although capable of being adjusted to various positions are, nevertheless, when so adjusted especially adapted to effectually resist the effect of forces tending to derange and displace them 10 from their adjusted positions, these forces arising ordinarily from the use of the adjusted member to accomplish some definite result—in other words, those forces incident to the working of the adjusted member to produce a designed effect.

The present invention is particularly applicable to a mounting for adjustable impressors or type-forming instrumentalities of that class which are employed for the making 15 of forged or wrought types; and I have in the present instance disclosed the invention as applied to the mounting of a plurality of type-forming dies grouped in sets and disposed upon a suitable carrier, serving 20 to maintain an adjusted group in proper position despite the forces to which the working die is subjected during the type-forming operation.

In the particular embodiment which I 35 have found to be the most advantageous each set of type-forming dies are borne by a die bar or slide, which latter is engaged with the carrier in a manner and by means embodying this invention.

40 In the practical use of a machine for making types and in which a plurality of sets of type-forming dies is comprised, mechanism will ordinarily be provided for shifting or adjusting that die carrier (in the event that a 45 plurality of the same are used) upon which is mounted the particular slide carrying the selected or chosen die. When the carrier shall have been adjusted to bring the proper die slide in line with the working or type-forming point and the given slide shall have 50 been furthermore shifted to bring the particular die in juxtaposition to said point, the operation of making the type may then be caused to take place through the instrumentality of appropriate mechanism.

The present improvements are especially designed to constitute an effective mounting for the adjustable die slides in those instances in which each die operates to make its type as the result of the compression of the die 60 against the blank and of a coincident subsidiary movement in the nature of a relative alternating motion of the type making members, which combined with each other effects a working movement well calculated to completely fill the angular recesses and hair-line spaces of the die. A mechanism operating to make types in this manner is set forth in my application Serial No. 79,359, filed Oct. 21, 1901.

70 In consequence of a working movement of this character, that is, one compounded of a feeding movement and a to-and-fro or alternating movement, the bar or slide upon which the die is borne is subjected during the 75 type making operation to stresses alternating from side to side and tending to displace the bar from its adjusted position, especially so when it is remembered that the slide itself is slidably engaged with the carrier on which it 80 is mounted to permit of its longitudinal adjusting movement with reference thereto. The present improvements are designed especially to render the shifted die bar rigid with 85 relation to the blank while the adjusted die is operating to form a type, yet nevertheless permitting the slide to be returned to its normal or inoperative position and to be again shifted with comparative facility. To 90 this end, the present improvements comprise a relation between relatively inclined or convergent thrust and reaction faces and substantially parallel coöperative faces especially adapted to give comparatively great 95 rigidity to the working die bar or slide, yet permitting the slide to be readily moved longitudinally for the purpose of returning the bar or slide to its normal position and bringing another chosen or selected die to the 100 working position.

105 In the drawing which accompanies the present specification, I have set forth in a general way a relation such as has been hereinbefore adverted to, such relationship existing among the surfaces of a die bar or slide mounted upon a cylindrical carrier or wheel.

110 In this drawing Figure 1 is mainly a sectional view on a plane transverse to the line of length of a die bar or slide, illustrating an embodiment of my present invention, the

scale being considerably enlarged as compared with the remaining figures. Fig. 2 is mainly a longitudinal section through a main carrier and shows a die bar or slide mounted 5 in a guideway on the periphery of the carrier, the view also exhibiting in a general way the manner of and the means by which any particular die bar or slide is adjusted. Fig. 3 is a perspective view of a die bar or slide having 10 a configuration and relation of surfaces such as set forth in Fig. 1. Fig. 4 is an elevational view illustrating in a conventional way an organization comprising a pair of main die carriers each having die bars or slides mounted 15 thereon and in which organization the shifting movement of the main carriers to bring a die bar in line with the working point, is compounded or arises from an angular movement about the axis of each main carrier 20 and also the movement of the pair of carriers about an axis exterior to them—in other words, the figure illustrates the die head or device of a machine or mechanism of that class in which the main die carriers are 25 each capable of an orbital and a rotary movement.

Similar characters of reference designate corresponding parts in all figures.

The present invention is especially designed to afford an effective mounting for a 30 bar or slide designed to be adjusted in the line of its length and when it has taken an adjusted position is subject to various forces whose line of application is more or less transverse to such line of length. As an instance 35 in which such conditions obtain, the employment of a bar or slide carrying impressors analogous to type-forming dies, matrices, etc., may be mentioned, which bars or slides upon 40 being shifted to adjust a chosen impressor into a given point for the purpose of making upon a blank or a portion thereof a type, are, by working movements in a plane more or less transverse to the line of length of the 45 bars, subjected to forces and stresses of such a nature as tend to impair the proper alignment or precisionized position of the slide. I have, therefore, for the purpose of illustrating an application and an embodiment of the 50 invention set forth in a general or conventional way, a main carrier or support B upon which are mounted a plurality of die bars or slides D, since the invention possesses an especial advantage not only for the mounting 55 of one such bar or slide, but is particularly suited for the mounting of an assemblage or plurality thereof in close or intimate relation. Ordinarily the main carrier, such as that designated by B, is more or less cylindrical in 60 form, although the form, construction or even employment of this particular detail of organization is in nowise concerned in the proper application of the invention. In the form of the main carrier illustrated herein, 65 however, the same comprises a peripheral

shell b extending from which is a web b' and having a hub b'' by which the carrier may be attached or supported upon a shaft, not shown. Each die slide D is so mounted as to be capable of a longitudinal or lengthwise 70 movement for the purpose of adjustment in a groove or channel, designated in a general way by C, formed in the peripheral portion of the main carrier.

Although the application of the invention 75 is in nowise limited to the employment of any special character or construction of die, I have, for the purpose of illustration, indicated as disposed upon the outer surface of each slide a series of dies, designated without 80 preference by E, and each adapted to form a type in cameo or relief upon the edge of a proper blank. Another feature illustrated in the drawings attached hereto relates more especially to the making of such types in 85 typographic proximity to each other along the edge of a blank. These features pertain to walls or supplemental dies at the sides of each type-forming die for protecting (see the wall e) the type immediately at the rear of 90 the forming type along the edge of the blank and a supplemental or space-forming die (see e') at the opposite side of the main die designed to form in advance of the forming type a space along the blank of sufficient 95 extent to remove some of the stock from the field of the type next to be formed. These features, however, bear no particular relation to the present invention but are fully disclosed in my applications Serial No. 100 56,165, filed April 16, 1901, and Serial No. 56,480, filed April 18, 1901. The type-protecting walls e are located at different distances from the supplemental or space-forming die e' since the width of the respective 105 type fields vary with the particular types which the dies are adapted to make.

For the purpose of best resisting the forces 110 incident to the forming of wrought types by an operation which involves a working movement for filling the cavity of the working die that creates forces and stresses extending transversely to the line of length of the slide upon which the die is carried as well as a pressure in the line of depth of the slide the 115 thrust receiving faces are preferably each inclined toward each other and toward the axis of depth of the bar (see the faces 2, 2'). These faces are located well toward the outer portion of the channel C, and are adapted to 120 be contacted by correspondingly inclined faces 2', 2', on opposite sides of the corresponding die slide. Preferably the inclination of these faces to the aforesaid axis will be equal in order to effect symmetry of action and reaction. The faces likewise are disposed in parallelism to each other and extend from end to end of the channel or groove in the carrier and of the bar. With respect 125 to the angle as seen in the cross section of 130

Fig. 1 made by each face to the aforesaid axis it is not designed that the same shall be an angle so acute as to result in a wedging of the slide under forcible compression in the 5 channel in which it is located, but that the angle shall be sufficiently obtuse to cause the elastic return of the metal of the sides of the channel to release the slide after a die has worked to permit the slide to be readily 10 shifted longitudinally.

Intimately concerned with the proper working of a die is the resistance to sidewise motion offered by that portion of the supporting slide located at the bottom of the 15 channel. In order that an ample leverage shall subsist adequate to effectually resist all side strains that may come upon the slide and which tend to tilt the same while the die is working, the shank or stem portion *d* of the 20 slide is extended well toward the center of the carrier, the channel *C* being made of sufficient depth to accommodate the same. It is this rear or shank portion of the slide that operates not only to steady the working 25 die but also to effectually guide the slide upon its adjustment, since it is designed that the slide shall spring outward slightly from its channel upon the release of the die from the blank, thus freeing the faces 2, 2 from 30 the thrust faces 2', 2', and permitting the slide to be readily shifted longitudinally of its channel. I find that the best results are attained by making the sides 3, 3 of the rear or shank portion of each slide substantially 35 parallel-sided and fitting them between similarly disposed side walls 3', 3', of the channel sufficiently tight to prevent side movement, although not so snugly as to prevent the free lengthwise adjustment of the slide.

40 The proportion and relation of the various faces and parts are such that, ordinarily, during the working of a die to form a type, the reaction surfaces are constituted, as aforesaid, by the inclined faces 2, 2, the bottom of 45 the slide not contacting under such circumstances with the bottom of the channel. When, however, a maximum pressure is exerted against the die, as in forming those types requiring relatively great amounts of 50 working to shape them, the bottom surface of the channel operates as a stop face to prevent undue inward movement of the slide, the faces 2, 2, by reason of the springing of the metal, opening sufficiently to permit the 55 entrance of the slide further than in the making of the usual run of types.

The disengagement of any slide from the channel in which it is seated (which the slide 60 might be disposed to do during the sliding thereof to adjust it to a required position) is prevented by a projecting rib 4 on the slide disposed longitudinally thereof and extending into a recess or groove 4' formed in the body of the main carrier. The location of 65 the recess or groove 4' in the carrier is such

that the latter is cut away to receive the projecting rib 4 at such a point as to weaken the main carrier between contiguous slides to the least extent under the application of forces acting substantially transversely to the 70 slides, that is, tangentially of the carrier. Since the rib 4 on each slide acts merely as a stop for preventing the displacement of the slide from position in the holding channel and does not aid in the type-forming operation 75 nor is it instrumental in resisting the stresses incident thereto, ample freedom of movement is provided between the faces of the rib and those faces on the carrier in juxtaposition to them. For facility of manufacture I 80 prefer to remove some of the metal lengthwise of the slide thus reducing the bearing surface thereof (see for instance the recessed portion 5 of the slide body).

In manufacturing a die carrier provided 85 with die slides organized and constructed as hereinbefore set forth, the same will ordinarily be subjected to proper machining operations designed particularly to produce commercially accurate and satisfactory working 90 faces and such as will render the slides interchangeable one with the other.

Although the mode and the mechanism for adjusting a carrier or a slide thereon to position is in nowise related to the application 95 of the invention disclosed herein, the slide, in the form thereof illustrated, is provided with a projecting tooth *F* adjacent to its rear end with which there is adapted to engage a slide adjuster *F'*, similar to the adjuster disclosed in my application hereinbefore referred to.

Having described my invention, I claim—

1. A bar combined with a support in a guideway of which the bar is shiftably 105 mounted, said guideway having adjacent to its mouth a thrust-receiving face oblique to the line of depth of the guide-way and a separate pressure-resisting face adjacent to its bottom, which latter face is adapted to prevent the lateral movement of the inner edge of the bar, during the working of the latter.

2. A bar combined with a support in a guideway of which the bar is shiftably mounted, said guideway having adjacent to 115 its mouth a pair of thrust-receiving faces at least one of which faces is oblique to the line of depth of the guide-way and a separate pair of pressure-resisting faces adjacent to its bottom, which latter faces are adapted to 120 prevent the lateral movement of the inner edge of the bar during the working of the latter.

3. A bar combined with a support in a guideway of which the bar is shiftably 125 mounted, said guideway having a pair of oppositely-inclined thrust-receiving faces adjacent to its mouth and a pair of relatively parallel pressure-resisting faces adjacent to its bottom, which latter faces are adapted to 130

prevent the lateral movement of the inner edge of the bar during the working of the latter.

4. A bar combined with a support in a guideway of which the bar is shiftably mounted, said guideway having adjacent to its mouth a pair of oppositely-disposed thrust-receiving faces of similar inclination oblique to the line of depth of the guideway and a pair of relatively parallel pressure-resisting faces adjacent to its bottom, which latter faces are adapted to prevent the lateral movement of the inner edge of the bar during the working of the latter.

15 5. A bar combined with a support in a guideway of which the bar is shiftably mounted, said guideway having a pair of oppositely-inclined thrust-receiving faces adjacent to its mouth operating as stop faces 20 during the ordinary working of the bar and a pair of relatively parallel pressure-resisting faces adjacent to its bottom, which latter faces are adapted to prevent the lateral movement of the inner edge of the bar during 25 the working of the latter.

30 6. A bar combined with a support in a guideway of which the bar is shiftably mounted, said guideway having adjacent to its mouth a thrust-receiving face oblique to the line of depth of the guide-way and a separate pressure-resisting face adjacent to its bottom, which latter face is adapted to prevent the lateral movement of the inner edge 35 of the bar during the working of the latter; and means for preventing the disengagement of the bar from the guideway during its shifting movement.

40 7. A bar combined with a support in a guideway of which the bar is shiftably mounted, said guideway having adjacent to its mouth a thrust-receiving face oblique to the line of depth of the guide-way and a separate pressure-resisting face adjacent to its bottom, which latter face is adapted to prevent the lateral movement of the inner edge 45 of the bar during the working of the latter; and means, comprising a groove formed in one member, and a rib extending from the other member into said groove for preventing the disengagement of the bar from the guideway during its shifting movement.

50 8. A bar combined with a support in a guideway of which the bar is shiftably mounted, said guideway having a pair of oppositely-inclined thrust-receiving faces adjacent to its mouth and a pair of relatively parallel pressure-resisting faces adjacent to its bottom, which latter faces are adapted to prevent the lateral movement of the inner 55 edge of the bar during the working of the latter; and means comprising a groove formed in one member and a rib on the other member extending into the groove for preventing the disengagement of the bar from the guideway.

9. A bar combined with a support in a guideway of which the bar is shiftably mounted, said guideway having a pair of oppositely-inclined thrust-receiving faces adjacent to its mouth and a pair of relatively parallel pressure-resisting faces adjacent to its bottom, which latter faces are adapted to prevent the lateral movement of the inner edge of the bar during the working of the latter; and means for preventing the disengagement of the bar from the guideway during its shifting movement. 70

10. A bar combined with a support in a guideway of which the bar is shiftably mounted, said guideway having a pair of oppositely-disposed similarly inclined thrust-receiving faces adjacent to its mouth and a pair of relatively parallel pressure-resisting faces adjacent to its bottom, which latter faces are adapted to prevent the lateral movement of the inner edge of the bar during the working of the latter; and means for preventing the disengagement of the bar from the guideway during its shifting movement. 80

11. A bar combined with a support in a guideway of which the bar is shiftably mounted, said guideway having a pair of oppositely-disposed similarly inclined thrust-receiving faces adjacent to its mouth and a pair of relatively parallel pressure-resisting faces adjacent to its bottom, which latter faces are adapted to prevent the lateral movement of the inner edge of the bar during the working of the latter; and means comprising a groove in one member and a rib on the other member extending into the groove for preventing the disengagement of the bar from the guideway during its shifting movement. 95

12. A die-bar provided with a plurality of dies, combined with a support in a guideway of which the bar is shiftably mounted, said guideway having adjacent to its mouth a thrust-receiving face oblique to the line of depth of the guide-way and a separate pressure-resisting face adjacent to its bottom, which latter face is adapted to prevent the lateral movement of the inner edge of the bar during the working of the latter. 100

13. A die-bar provided with a plurality of dies, combined with a support in a guideway of which the bar is shiftably mounted, said guideway having adjacent to its mouth a pair of thrust-receiving faces one at least of which faces is oblique to the line of depth of the guide-way and a separate pair of pressure-resisting faces adjacent to its bottom, which latter faces are adapted to prevent the lateral movement of the inner edge of the bar during the working of the latter. 110

14. A die-bar provided with a plurality of dies, combined with a support in a guideway of which the bar is shiftably mounted, said guideway having a pair of oppositely-in- 120

clined thrust-receiving faces adjacent to its mouth and a pair of relatively parallel pressure-resisting faces adjacent to its bottom, which latter faces are adapted to prevent the 5 lateral movement of the inner edge of the bar during the working of the latter.

15. A die-bar provided with a plurality of dies, combined with a support in a guideway of which the bar is shiftably mounted, said 10 guideway having a pair of oppositely-inclined thrust-receiving faces adjacent to its mouth operating as stop faces during the ordinary working of the bar and a pair of relatively parallel pressure-resisting faces adjacent 15 to its bottom, which latter faces are adapted to prevent the lateral movement of the inner edge of the bar during the working of the latter.

16. A die-bar provided with a plurality of 20 dies, combined with a support in a guideway of which the bar is shiftably mounted, said guideway having adjacent to its mouth a thrust-receiving face oblique to the line of depth of the guide-way, and a pressure-resisting face adjacent to its bottom, which latter face is adapted to prevent the lateral movement of the inner edge of the bar during the working of the latter; and means for preventing the disengagement of the bar from 25 the guideway during its shifting movement.

17. A die-bar provided with a plurality of dies, combined with a support in a guideway of which the bar is shiftably mounted, said 30 guideway having adjacent to its mouth a thrust-receiving face oblique to the line of depth of the guide-way, and a pressure-resisting face adjacent to its bottom, which latter face is adapted to prevent the lateral movement of the inner edge of the bar during 35 the working of the latter; and means, comprising a groove formed in one member, and a rib extending from the other member into said groove for preventing the disengagement of the bar from the guideway during its 40 shifting movement.

18. The combination with a carrier, of a plurality of die-bars mounted in guideways formed in the periphery of the carrier, each guideway having a pair of oppositely-inclined thrust-receiving faces adjacent to its 50 mouth, and a pair of relatively parallel pressure-resisting faces adjacent to its bottom, which latter faces are adapted to prevent the lateral movement of the inner edge of the bar during the working of the latter.

19. The combination with a carrier, of a plurality of die-bars mounted in guideways formed in the periphery of the carrier, each 55 guideway having a pair of oppositely-inclined thrust-receiving faces adjacent to its mouth, and a pair of relatively parallel pressure-resisting faces adjacent to its bottom, which latter faces are adapted to prevent the lateral movement of the inner edge of the bar

during the working of the latter; and means, 65 comprising a groove formed in that portion of the carrier between contiguous guideways, and a rib upon the corresponding die-bar extending into the groove, for preventing the disengagement of the die-bar from the guideway 70 during its shifting movement.

20. A die bar provided with a plurality of dies, combined with a support in a guide-way of which the bar is shiftably mounted, said guide-way having a somewhat greater depth 75 than the depth of the die bar and also having adjacent to its mouth a pair of thrust-receiving faces making substantially the same oblique angle with the line of depth of the guide-way and a pair of parallel pressure-resisting 80 faces adjacent to the bottom of the guide-way and in line with the line of depth thereof which latter faces are adapted to prevent the lateral movement of the inner edge of the bar during the working of the latter, and means 85 for preventing the disengagement of the bar from the guide-way during its shifting movement.

21. A bar combined with an axially mounted support in a guideway of which the bar is 90 shiftably mounted, said guideway having a thrust receiving face and a pressure resisting face relatively remote from the thrust receiving face.

22. A die-bar provided with a plurality of 95 dies combined with a support in a guideway of which the bar is shiftably mounted and means for retaining the bar in the guideway and means effective upon the inauguration of the work of the bar for positioning the same 100 in the guideway.

23. A bar having a wedge shaped back combined with a support having a guideway provided with a wedge shaped mouth flaring outwardly for engagement with said wedge 105 shaped back and in which guideway said bar is slidable.

24. A die-bar provided with a plurality of dies and having a wedge shaped back face combined with a support in a guideway of 110 which the bar is shiftably mounted, the guideway having outwardly flaring thrust and guide faces for engagement with said wedge faces.

25. A bar combined with a support in a 115 guideway in which the bar is shiftably mounted, said guideway having a wedge shaped outwardly flaring mouth for guiding and thrust engagement with the wedge shaped back of the bar.

26. A bar having a wedge shaped back combined with a support in a guideway of which a bar is shiftably mounted, said guideway having a wedge shaped outwardly flaring mouth for guiding and thrust engagement 120 with the wedge shaped back of the bar.

27. A die-bar combined with a support having an outwardly flaring mouth support-

ing and guiding the wedge shaped back of the bar, and having a retaining face for engaging a retaining face upon the bar.

28. A die-bar combined with a support in 5 a guideway of which the bar is mounted for longitudinal movement, said guideway and die-bar each having a thrust receiving face and a pressure resisting face relatively remote from the thrust receiving face.

10 29. The combination with a die-bar having 10 a pair of oppositely inclined thrust faces at its rear near its die face, a thrust face at its rear parallel with its die face and a pair of relatively parallel pressure faces adjacent the 15 rear thrust face, of a support in a guideway 15 of which the bar is shiftably mounted, said guideway having a pair of oppositely-inclined thrust-receiving faces adjacent to its mouth operating as stop faces for the inclined 20 thrust faces of the bar during the ordinary 20 pressure of working of the bar, and a pair of relatively parallel pressure-resisting faces adjacent to its bottom, which latter faces are 25 adapted to engage the pressure face of the 25 bar and prevent the lateral movement of the inner edge of the bar during the working of the latter, and a thrust receiving face at the 30 said bottom for receiving the thrust of the face at rear of bar.

30. A bar combined with a support in a 30 guideway of which the bar is shiftably mounted, said guideway having a pair of oppositely-inclined thrust-receiving faces adjacent to its

mouth operating as stop faces during the ordinary pressure of working of the bar and 35 capable of yielding upon excessive pressure of working, and a pair of relatively parallel pressure-resisting faces adjacent to its bottom, which latter faces are adapted to prevent the lateral movement of the inner edge 40 of the bar during the working of the latter, said bottom constituting a thrust receiving face under excessive pressure of working.

31. The combination with a support provided with a guideway, said guideway having 45 a thrust receiving face at its bottom, a pair of pressure resisting and guide faces disposed adjacent the bottom and parallel one with the other, and adjacent to its mouth, a pair of outwardly flaring thrust-receiving 50 faces, of a die-bar provided with a plurality of dies and shiftably mounted in said guideway, said bar having a pair of thrust faces disposed in position to engage the said outwardly flaring thrust faces at the mouth of 55 the guideway, pressure-resisting faces disposed one parallel with the other for engaging the pressure-resisting faces of the guideway, and a thrust face at the back for engaging the thrust receiving face at the bottom of 60 the guideway.
